UNITED STATES PATENT OFFICE.

JOSEPH G. HUTCHINSON, OF ATTLEBOROUGH, MASSACHUSETTS.

DESIGN FOR A DISPLAY SHOW-CASE.

SPECIFICATION forming part of Design No. 32,413, dated March 27, 1900.

Application filed November 13, 1899. Serial No. 736,884. Term of patent 3½ years.

To all whom it may concern:

Be it known that I, JOSEPH G. HUTCHINSON, a citizen of the United States, residing at Attleborough, in the county of Bristol and State of Massachusetts, have invented and produced a new and original Design for a Display Show-Case, of which the following is a specification, reference being had to the accompanying drawing, forming a part thereof.

The figure is a perspective view of my design.

My design consists of a circular concaveous base, a standard extending upward from the center thereof, a circular tray surmounting said standard and having an upwardly-extending vertical-sided circumferential rim and raised radial ribs arranged and disposed as shown, said ribs forming sector-shaped receptacles, and a circular transparent disk

with a knob-post extending upward from the center thereof.

In the drawing, A represents the base, B the standard, and C the tray, having the radial ribs *c c*, forming the sector-shaped receptacles *d d*, and D represents the transparent disk with the concentric knob-post *e*.

Having described my invention, what I claim as new, and desire to secure by Letters Patent, is—

The design for a display show-case; as herein shown and described.

In testimony whereof I have signed my name to this specification in the presence of two subscribing witnesses.

JOSEPH G. HUTCHINSON.

Witnesses:

HENRY MARSH, Jr.,
DENNIS H. SHEAHAN.
